Primary Examiner — Natasha Vujcic*Assistant Examiner* — Gilbert B Ford(74) *Attorney, Agent, or Firm* — Dicke, Billig & Czaja, PLLC(57) **CLAIM**

We claim, the ornamental design for a disinfecting tool, as shown and described.

DESCRIPTION

FIG. 1 is a front perspective view of a disinfecting tool in accordance with principles of the present design;

FIG. 2 is a front end view thereof;

FIG. 3 is a rear end view thereof;

FIG. 4 is a right side view thereof;

FIG. 5 is a left side view thereof;

FIG. 6 is a top plan view thereof; and,

FIG. 7 is a bottom plan view thereof.

The broken lines shown in the figures illustrate portions of the disinfecting tool that form no part of the claimed design.

1 Claim, 7 Drawing Sheets(56)
